HANDLING DEVICE

Dudley M. Lontz, Georgetown, Conn.

Application December 13, 1944, Serial No. 568,027
6 Claims. (Cl. 294—116)(Granted under the act of March 3, 1883, as
amended April 30, 1928; 370 O. G. 757)

The invention described herein may be manufactured and used by or for the Government for governmental purposes without the payment to me of any royalty thereon.

This invention relates to a device for picking up or depositing articles in confined spaces where the gripping and releasing of the object must be automatically brought about.

The invention is exemplified in a device more particularly designed and intended for the purpose of removing projectiles from within large mortars and lowering projectiles into the tubes of such mortars. While the invention thus finds a useful application in the field of military supplies, it is to be understood that it is not to be limited thereto but is applicable to the handling of other objects, especially under comparable circumstances.

While projectile handling devices embodying the invention can be made for use with mortars of any caliber, the particular device hereinafter described in detail is designed for use with a 10-inch mortar, the projectile for which may weigh in the neighborhood of 250 pounds.

It is sometimes necessary to remove from within a mortar a projectile which has been loaded into it. For example, an order to cease firing or to change the powder charge may be received after the mortar has been loaded. According to the present invention a device is provided which is designed to be suspended from a single cable and which, when lowered into the tube of a mortar, will automatically grip a projectile therein so that the projectile can be lifted out therewith.

Conversely, the device can be employed to lower a projectile into the tube of a mortar and to release it automatically when it reaches the bottom. Ordinarily, a projectile can be dropped into the mouth of the mortar, its fall being amply cushioned by the compression of air beneath it, but if a gradual lowering of the projectile in the tube is desired, the device can be used for this purpose also.

The device hereinafter described comprises a housing consisting of two telescoping parts which move relatively to operate a set of grippers mounted therein. The two parts are arranged so that when the device is resting on the ground or other equivalent support, the lower member acts as a base and the upper member tends to telescope therewith by reason of its weight. The cable for lifting the device is attached to the upper member so that it is the first part to be raised. The lower member starts to rise when the upper member has reached the limit of relative move-

ment between the members. As hereinafter explained, the function to be performed by the device, that is, gripping a projectile or releasing it, is determined by regulation of the extent of relative movement of the members.

For a more complete understanding of the invention, reference may be had to the following description thereof, and to the drawings, of which:

Figure 1 is a sectional elevational view of an embodiment of the invention.

Figures 2, 3, 4 and 5 are half-views of the same, showing the parts in different relative positions.

The device illustrated in the drawings includes a cylindrical housing consisting of an upper part 10 which slides telescopically in a lower part 12. The upper part 10 is provided with an integral top 14 from the center of which a ring or hook 16 projects upward and a fixed shank 18 projects downward. The ring 16 is adapted to be secured to a suitable single-cable purchase by which the entire device may be raised and lowered. The shank 18 terminates at its lower end in a cam member 20 which has the shape of an inverted saucer. To the inner wall of the housing part 10 is secured a ring 22. This ring has a bevelled cam face 24 which forms an edge 25 with the top face of the ring and is situated slightly above the level of the cam member 20 for a purpose hereinafter described.

Vertically slidable on the shank 18 is a collar 30 which has an annular bottom face 32 and an inner inclined or frusto-conical cam face 34. This collar is held in either one of two positions on the shank by a bell-crank 36 which is rockably mounted at 38 to a bracket 40 secured to the inner wall of the housing part 10. The horizontal arm 42 of the bell-crank is forked to embrace half of the collar 30. At the ends of forked arm 42 are lugs or rollers 44 which ride in a circumferential groove 46 in the collar to control the position of the collar on the shank. The collar and bell-crank constitute control means for the device, as hereinafter explained.

The vertical arm 50 of the bell crank projects up through a slot 52 in the housing top 14 and serves as a manually operable lever for raising or lowering the collar 30 from one position to the other. The two positions of the collar may conveniently be determined by a pair of notches 54 and 56 which receive a pawl 58 carried by the lever 50 and operable in a manner generally employed and well known in the art.

As previously stated, the upper housing part 10 slides telescopically within the lower part 12, the extent of such movement being limited, when

pawl 58 is in the notch 56, by a stop element 60 which is on the outer surface of the upper part 10. Mounted within the lower housing part 12 are a set of gripping levers 62, three such grippers being sufficient for most purposes although more may be provided if desired. Each of these levers is rockably mounted near its midpoint at 64 on a bracket 66 which is secured to the inner wall of the housing part 12. At the upper extremity of each lever 62 is a point or nose 71 which serves as a stop when engaged by the annular bottom face 32 of the collar 30 when the latter is in its lower position with respect to the housing part 10. The collar 30 thus serves to limit the range of telescoping movement between the housing parts. When the collar is elevated, however, the telescoping movement is limited by the stop 60. In such case, the additional telescoping movement permitted by the elevated position of the collar allows the notches 69 in the gripping levers to catch over the edge 25 of the cam ring 22, thus locking the levers in the open position. The levers can be released from this locked position by moving the collar 30 to its lower position. The tops of the levers are engaged by the cam surface 34 and moved inward to disengage the notches 69 from the edge 25. Each lever 62 is provided at its lower end with a gripping element or claw 72 which is adapted to engage in a corresponding recess in the object to be handled by the apparatus. In the device illustrated the claws 72 are arranged to enter a peripheral groove 74 in a projectile 76 near the nose 78 thereof. Furthermore, the bottom rim of the lower housing part 12 is turned in and up to form a flange 80 adapted to seat against the nose 78 of a projectile when the claws 72 are at the level of the groove 74. Each lever 62 projects through a slot 82 in the flange 80 which limits the inward and outward movements of the claws 72. Springs 84 which extend from the flange 80 to adjacent points of the levers tend to maintain the levers in the "closed" position in which the claws are as near to the axis of the device as the slots 82 permit.

To retrieve a projectile from the barrel of a mortar, the device is operated as follows: The hand-lever 50 is set with the pawl 58 in the inner notch 54, which means that the collar 30 is in its lower position. The whole device, which is suspended by the ring 16, is lowered into the barrel of the mortar in which the projectile 76 is located. When the claws 72 engage the conical surface of the nose of the projectile, they tend to take the weight of the lower housing part 12 and also to swing the lower parts of the levers outward. This results in a downward movement of the upper part 10 relative to the lower part 12, and the engagement of the cam face 24 on the cam edges 68 helps to rock the levers against the tension of the springs 84 so that the claws 72 can enter the groove 74 as illustrated in Figure 2. When the collar 30 is in its lower position, its bottom surface 32 is engaged by the nose 71 of each lever before the notch 69 can rise high enough to catch over the edge 25 of the ring 22. Thus, when the upper part 10 is lifted by the ring 16, the cam surface 24 moves up from the cam edges 68, the cam member 20 bears on the edges 70 and, with the springs 84, operates to hold the claws 72 tightly engaged in the groove 74 of the projectile as the latter is lifted with the device. When the projectile is clear of the mortar, it is lowered toward the ground or other support. While the device is still suspended, the hand lever 50 is shifted to its outer position, moving the col-

lar 30 to its upper position as in Figure 3. The lowering is then continued until the weight of the device is taken by the projectile, whereupon the upper housing part 10 moves down by its own weight to telescope into the lower part 12 so that the cam edge 68 of each lever 62 rides up the cam surface 24 until the notches 69 catch over the edge 25, as shown in Figure 4, further telescoping movement of the upper part 10 being prevented by the stop 60. In this position the claws 72 are spread so that they are clear of the groove 74, and the device can be lifted from the deposited projectile. The hand lever 50 can now be shifted to its inner position as shown in Figure 5. This moves the collar 30 downward and causes the cam surface 34 to engage the upper portions of the cam edge 68, thus disengaging the notches 69 from the edge 25 and permitting the lower housing part 12 to drop to the relative position shown in Figure 1. The device is now ready to retrieve another projectile or to be attached to a projectile for the next loading.

If it is desired to use the device to lower a projectile into the interior of a mortar, or other confined space, the hand lever 50 is set in its inward position after having been shifted to such position when the device was suspended, and the projectile is gripped as shown in Figure 2 and hereinbefore described. When the projectile is lifted, the lever 50 is shifted outward, and the projectile is then lowered into the mortar until it reaches the bottom of the barrel. The upper housing part 10 then descends further until the claws are swung out and locked as in Figure 4. The device can then be raised out of the mortar, leaving the projectile therein.

It is to be understood that the invention is not to be limited to the particular embodiment herein described but may include such modifications and changes as come within the scope of the appended claims.

I claim:

1. An object-handling device comprising upper and lower parts which are relatively movable through a limited range, a set of gripping levers rockably mounted on one of said parts and operable by relative movement between said parts to rock between a gripping position and an open or releasing position, control means selectively operable in one position to limit relative movement between said parts to said limited range and in another position to permit additional relative movement beyond said range and means responsive to said additional relative movement of the parts to lock said levers in their open position.

2. An object-handling device comprising upper and lower parts which are relatively movable through a limited range, a set of gripping levers rockably mounted on one of said parts and engageable by the other part to rock said levers by relative movement between the parts from a gripping position to an open or releasing position, a control member carried by said other part and movable from a position in which it acts as a stop to limit relative movement between said parts to a position which permits additional relative movement and means responsive to said additional relative movement to lock said levers in the open position.

3. An object-handling device comprising upper and lower parts which are relatively movable through a limited range, a set of gripping levers rockably mounted on the lower part and engageable by the upper part to rock said levers by relative movement between the parts from a gripping

position to an open or releasing position, a control member carried by said upper part and movable relatively thereto from a position in which it acts as a stop to limit relative movement between said parts to a position which permits additional relative movement between the parts, and means responsive to said additional relative movement to lock said levers in the open position, said control member including means for releasing said levers from their locked position.

4. An object-handling device comprising a housing consisting of upper and lower cylindrical parts in telescoping relation, a set of gripping levers pivotally mounted within the lower part and rockable between a gripping position and an open position, said levers having gripping claws at their lower ends and cam edges and notches adjacent to their upper ends, a cam ring within said upper part engageable by said levers to rock the same when said upper part moves downward with respect to said lower part, a stop member carried by said upper part and engageable by the upper ends of said levers to stop telescoping movement between said parts before said notches in the levers can catch on said ring, and means for elevating said stop member to permit additional telescoping movement sufficient to cause said notches to catch on said ring to maintain the levers in open position.

5. An object-handling device comprising a housing consisting of upper and lower telescoping parts, a set of gripping levers pivotally mounted within the lower part, said levers having gripping claws at their lower ends and cam edges and notches adjacent to their upper ends, a cam ring mounted within the upper said part, said ring having a surface engageable by cam edges of said levers to rock said levers to their open position, said ring also having an edge on which said notches may catch to lock the levers in open po-

sition, and control means carried by said upper part, said control means including a collar vertically movable with respect to said upper part and a hand lever operatively connected to said collar, said collar having an annular bottom surface engageable when in lowered position by the upper ends of the levers to stop telescoping movement of the parts before the notches catch on said ring, said collar when elevated permitting said notches to catch on said ring, said collar having a cam surface adapted to disengage said notches from said ring when the collar is lowered.

6. An object handling device comprising upper and lower cylindrical telescoping parts, means on the upper part to receive a hoisting line, a set of gripping levers pivotally mounted on the lower part to rock between a gripping position and an open position, spring means pressing said levers toward their gripping position, cam edges and notches adjacent to the upper ends of said levers, a cam ring mounted within said upper part and engageable by said levers during telescoping movement of said upper part to rock said levers to the open position, said ring having an upper edge upon which said notches may catch to lock the levers in open position and control means carried by the upper part, said control means comprising a collar vertically movable to upper and lower positions with respect to said upper part and a manual lever operatively connected with said collar, said collar having a bottom surface adapted to engage the upper ends of said levers to act as a stop when the collar is in its lowered position to prevent said notches from catching over the edge of said cam ring, said collar also having a cam surface adapted to engage the upper ends of the locked levers when the collar is lowered to disengage the notches from said ring.

DUDLEY M. LONTZ.
